UNITED STATES PATENT OFFICE.

JAMES W. TAYLOR, OF SAN ANTONIO, TEXAS.

PUMPING APPARATUS.

Application filed March 16, 1925. Serial No. 15,762.

To all whom it may concern:

Be it known that I, JAMES W. TAYLOR, a citizen of the United States, residing at San Antonio, in the county of Bexar and State of Texas, have invented certain new and useful Improvements in Pumping Apparatus, of which the following is a specification.

This invention relates to an improved flowing or pumping apparatus for removing liquids from oil wells, the object of the invention, generally stated, is the provision of apparatus of this character which, when inserted within a well, will serve to force the liquid in the well to the surface by means of the expansive power of the natural gas generated or contained within the well.

In accordance with the invention there is provided a pumping apparatus for the purpose set forth consisting broadly of a well casing in which is positioned the centrally disposed flow line or tubing. This tubing carries, at a position near the lower part of the well, a flow hood in which the natural gas of the well is trapped, there being an entry between the hood and the flow line by means of which the trapped expandable fluid is permitted to enter the flow line to effect the elevation of the liquid therein. The entry is provided with an associated valve mechanism for controlling fluid flow therethrough, and the particular feature of the present invention resides in the provision of automatically operating means for controlling the operation of the valve mechanism, wherein the arrangement is such that when the fluid pressure within the casing reaches a predetermined pressure, the valve mechanism will be open to permit the expelling fluid to enter the flow line and expand, and when the gas pressure in the casing is reduced to a predetermined pressure, the valve mechanism will be operated to close the entry and to arrest further liquid flow through the flow line or tubing until the gas pressure has been again built up to a point permitting of the opening of the valve mechanism.

With these and other objects in view, as will appear as the description proceeds, the invention consists in the novel features of construction, combinations of elements and

arrangements of parts hereinafter to be fully described and pointed out in the appended claims:

In the accompanying drawing:

Figure 1 is a side elevation of the pumping or well flowing apparatus comprising the present invention, 55

Figure 2 is a vertical sectional view taken through the apparatus at the upper end of the well casing, and 60

Figure 3 is a vertical sectional view taken through the well casing, the flow line tubing and the associated hood and valve mechanism. 65

Referring to the drawings, the numeral 1 designates a standard form of well casing which is adapted to be inserted into a drilled well opening and to extend from the surface of the well to the oil producing sands. Within the casing extending axially and longitudinally therethrough is a flow line or tubing 2 having a perforated lower end 3 which rests upon the bottom plug 4 provided in a well screen 5, the lower end of the screen 5 resting upon the bottom of the well. By 70 this it will be seen that a standard construction is provided, although other forms may be used, in which oil will be permitted to enter the flow line and to arise therein, as well as in the casing, by the natural pressure 75 or flow of the oil or liquid, and that the height which the oil will reach in the flow line and the casing will vary in accordance with the natural pressures existing in each well. 80

Applied to the upper end of the casing 1 is a casing head 6, through which the upper end of the flow line extends and in which the flow line is suitably sealed, as will be hereinafter described, to confine within the 85 casing the natural gases of the well for the purpose of embodying these gases in the expelling of the liquid.

The flow line 2 in this instance includes relatively movable upper and lower sections 7 and 8 respectively. The upper section is provided at its lower end with a threaded coupling 9, which supports a nozzle 10, constructed to restrict the diameter of the flow line to facilitate the liquid's expulsion. The 100

lower end of the nozzle is threaded to receive the cap section 11 of a flow hood designated generally by the numeral 12.

The hood consists of a cylindrical casing 13, closed at its upper end and open at its lower end as indicated by the numeral 14. The diameter of the casing 13 is slightly less than the internal diameter of the casing 1, so that fluid arising within the casing 1 is circulated around the hood and into the upper part of the casing 1 above the flow hood. The casing 13 may be of any suitable length. It will be seen that by this construction the natural gas delivered from the well will accumulate in part in the upper closed end of the hood and will be prevented from expanding while retained within the hood, by reason of the fluid pressure contained within the casing 1 above the hood.

In order to admit the gas into the flow line to expel the liquid therein, there is provided a valve mechanism which in this instance consists of a sleeve 16, provided with an annular enlargement 17 having a recessed upper end 18 in which is seated a soft metal washer 19, while the lower end of the enlargement is provided with a rounded shoulder 19^a. The ends 18 and 19^a of the enlargement 17 are adapted for engagement with a rounded annular bead 20 provided on the lower end of the cap section 11 and with a beveled seat 21 provided internally upon a tube 22 threaded as at 23 in connection with the cap section. The lower end of the tube 22 has an opening provided therein for the sliding reception of the sleeve 16, and said opening possesses a greater diameter than the external diameter of said sleeve at this point so as to permit of fluid passage through the interior of said tube. The upper end of the sleeve 16 is provided with a plurality of passages or entries 24, and it will be seen that when the enlargement 17 is positioned midway in the length of the tube 22, or in other words, when the parts 18 and 19^a are spaced from the seats 20 and 21, fluid will be permitted to flow from beneath the hood, through the tube 22 and thence by way of the passages 24 into the liquid contained within the flow line.

It will be understood that the fluid pressures within the flow line and within the casing 1 or the hood 12 are substantially equalized or balanced adjacent the passages 24, so that a slight excess of pressure in the casing 1 or within the flow hood 12 will be sufficient to force or permit the expelling gas to enter the flow line against the resistance offered by the hydro-static head of the column of liquid in the flow line.

Since the gas is maintained in its normal compressed state within the hood by the fluid pressure above the same, it follows that when this gas enters the flow line, that the liquid pressure in the latter prevents im-

mediate expansion of the gas. In other words the gas will enter the flow line in small bubbles which by virtue of their natural buoyancy will arise vertically through the liquid in the flow line and will expand so as to become gradually enlarged as the bubbles ascend the flow line. This expansion, of course, becomes greater when the hydro-static pressure thereon is gradually diminished by the rise thereof in the column of liquid, since as the bubbles near the top of the flow line the liquid pressure becomes correspondingly smaller. The bubbles are then permitted to expand to their maximum point wherein they substantially fill the tubing and therefore serve in the capacity of pneumatic pistons for expelling the liquid at the top of the flow line. The bubbles follow one another in very rapid succession at accelerated speed of travel and consequently can expel a large volume of liquid from the tubing.

Since the apparatus described relies upon the natural gas pressure in the well to expel the liquid, it follows that in most wells this pressure can not be generated sufficiently to provide for a continuous flowing of the well, and therefore it is necessary to provide for an intermittent opening and closing of the valve mechanism so that the pressure of the gas may be built up and released in "heads" or impulses for the purpose of expelling the fluid. It is a primary object of the present invention to automatically regulate the opening and closing of the valve mechanism, in contrast to manually operated structures. Since the lower section 8 of the tubing rests upon the bottom of the well, I provide a structure by means of which the upper section of the flow line together with the hood may be raised and lowered at intervals so as to cover and uncover the ports or passages 24.

The structure for accomplishing this object is disclosed in Figure 2 and consists of a cylinder 25 formed with the casing head 6. The cylinder 25 includes a base section 26 arranged to hold a suitable quantity of a liquid, and the upper rim of the section 26 is shouldered as at 27 for the reception of a gasket ring 28. Resting upon the gasket 28 is the upper section 29 of the cylinder 25, which has its lower end flanged as at 30 and arranged in registration with a similar flange 31 provided upon the lower section, and threaded fastening devices 32 are used for connecting the flanges 30 and 31 so as to draw the upper section 29 of the cylinder firmly down upon the gasket 28 so as to render the entire cylinder fluid tight.

Mounted within the cylinder for vertical reciprocation is an inverted cup shaped piston 33, the walls of which being in engagement with the inner wall of the gasket 28 so as to prevent undue passage of the liquid

in the base section into the upper section. The base section 26 carries an axially disposed tubular stem 34 which arises in the piston 33 and serves to limit the downward movement of the piston. The upper end of the stem 34 is apertured as at 35 and the internal diameter of the stem 34 is such, in relation to the tubing 2, that the gas pressure which builds up in the casing will be permitted to flow through the apertures 35 so as to exercise its expansive pressure upon the surface of the liquid in the base section 26 and the under surface of the piston 33.

Integrally formed upon the upper part 15 of the piston is a packing gland 36 containing a packing ring 37 which is compressed around the flow line, and threaded within the gland 36 is a tube 38 which also extends upwardly through a packing gland 39 provided in the upper section 29 of the cylinder. The upper end of the tube 38 projects through the gland 39 and is provided with a race-way upon which is seated a thrust bearing 40, which engages with the under 25 surface of the hub of an adjusting wheel 41. This wheel is provided with an internally threaded hub which engages with the raised threads 42 provided upon the flow line, and it will be seen that by rotating the 30 wheel 41, the flow line may be adjusted vertically to govern the extent of opening of the valve mechanism.

In operation, the tubing or flow line 2 is supported by the wheel 41 resting upon 35 the bearing 40, which in turn is supported by the piston 33. The threads 42 permit the adjustment of the tubing with respect to the stem 34 so that when the piston has lifted the tubing to the desired or necessary 40 height to open the valve mechanism under the hood, the metallic gasket 43, carried by the flow line, will seat against the seat 44 surrounding the lower end of the stem 34 which, in turn, will shut off the gas flow into 45 the chamber 12 and thereby stop further upward movement of the tubing.

The chamber in the lower section 26 of the cylinder is filled with oil or other liquid to the level shown by the dotted line 45, thus giving a liquid seal in the cylinder, since the gas can not escape from the cylinder until it has forced all of the oil through the gasket 28 which, however, normally obstructs and will prevent such seepage. 50 Should, however, the gasket become sufficiently loose, the leak will be detected by the seepage of the liquid from the cylinder by way of the small valve 46 situated in the bottom of the upper section 29. A valve 55 47 is employed in a pipe line 48 which, includes a vertically extending stand pipe 49 arranged in the base 26. Normally, the pipe 49 is arranged above the level 45, and a small opening 50 is formed in the pipe below the 60 normal level of the oil, so that when the

valve 47 is open, the operator may determine by the escape of the oil or gas whether or not the oil level 45 is at its required point in the cylinder. If the oil level is above the opening 50 oil will issue through the 70 valve 47, and if the oil level is below the opening 50 air or gas will issue. Connected with the line 48 is a vertically disposed pipe line 51, arranged exteriorly of the cylinder 75 25, and it is through this line that the supply of liquid in the cylinder may be replenished from time to time.

Assuming that gas pressure exists in the well casing, and the tubing has been raised to a point where the gasket 43 contacts with the seat 44, it is evident that the tubing could not be lowered unless the gas pressure were released from the casing. Therefore, the upper chamber is provided in the cylinder as at 29, and by the employment of 80 which means are provided for lowering the tubing irrespective of the gas pressure in the well casing; for it will be seen that if gas pressure be admitted to the upper chamber, by way of the pipe line 51, that the 85 pressure in the two chambers will be equalized, so that the tubing will be permitted to lower by responding to gravity. As soon as pressure is released from the upper chamber, effected by way of the valves 52 and 53, 90 the tubing will again rise until the washer or gasket 43 engages with its seat 44. Normally a pressure sufficient to operate the 95 piston will always be carried in the well casing. However, it will be seen that the tubing can be raised and lowered by simply 100 rotating the hand wheel 41, and the well operated in this manner if desired.

In view of the foregoing description, taken in connection with the accompanying 105 sheets of drawing it will be seen that the present invention provides simple and automatically operating means for effecting the flowing of an oil well by the use and application of the natural gas pressure contained 110 in the well. As the gas pressure builds up under the hood and in the upper portion of the casing 1, there is an elevation on the part of the piston so as to effect the elevation of the upper section 7 of the tubing 115 2. This upward movement on the part of the tubing results in the opening of the valve mechanism which permits of the flow of the gas from under the hood into the tubing, so that the gas may be used, as 120 previously described, for the expelling of the liquid from the well. It will be seen that as the gas is released from under the hood and the liquid level in the casing recedes there will be a corresponding expansion and decrease in pressure of the gas in 125 the upper part of the casing acting upon the piston, which results in the lowering of the piston, and the flow line to again close the valve mechanism so as to permit of the 130

building up of the fluid pressure under the hood. In the event, however, that the gas pressure in the upper part of the well casing becomes so excessive as to maintain the piston in its elevated position continuously or for relatively extended periods, it is necessary to use the pipe line 51 for the purpose of admitting a portion of the fluid or gas into the upper chamber of the cylinder, 10 so as to permit of the balancing of fluid pressures on the piston and the restoration of the flow line to its lowered position wherein the valve mechanism is closed. Again, by balancing the pressures on the 15 piston the valve mechanism may be maintained in a closed position for indefinite periods in order to permit the gas generated within the well to be drawn off through the pipe line 54, forming a part of a supporting frame 55, to other wells wherein the gas supply needs to be augmented. The control thus provided by the cylinder 25 is thus rendered automatic or may be subject to manual control so as to cover the flowing of 20 the well at any time.

What is claimed is:

1. In oil well apparatus, a casing, a flow line vertically shiftable within said casing, a normally closed head provided on the 20 upper end of said casing and including a cylinder surrounding said flow line, a piston within said cylinder connected with said flow line, a valve structure in said flow line and capable of being opened and lowered by a movement of the flow line to establish communication between the casing and said flow line, and means for confining gas in the upper end of said casing and permitting the application of the same 30 to one or both sides of said piston to govern the raising and lowering of the flow line and the operating positions of the valve structure therein.
2. In oil well apparatus, a casing normally sealed at its upper end, a flow line vertically shiftable within said casing, a valve structure in said flow line operated by the rise and fall of the flow line to establish communication between the casing and the 40 interior of said flow line, a head provided upon the upper end of said casing including a pressure chamber through which said flow line projects, a piston on said flow line within said chamber, a liquid seal between said piston and the walls of said chamber, and a valve controlled passage leading from said casing into said cylinder to permit the normal gas pressure of the well to build up within said casing to act 50 upon said piston so as to control the operating positions of the valve structure.
3. In oil well apparatus, a casing, a flow line vertically adjustable within said casing, a head provided upon the upper end 60 of said casing and including a chamber 65 through which said flow line projects, a piston disposed within said chamber and connected to said flow line, a valve controlled port leading from said casing into the under part of said chamber to permit gas pressure built up within said casing to act upon the under side of said piston to raise said flow line, and means for diverting the gas pressure from the under to the upper part of said chamber so as to balance 70 the gas pressure on said piston.
4. In oil well pumping apparatus, a casing, a flow line vertically adjustable within said casing, a valve structure in said flow line opened and closed by vertical movement on the part of said flow line with respect to said casing, a head at the upper end of said casing having a chamber formed therein, a piston arranged for movement within said chamber and connected with 80 said flow line, an entry establishing communication between the interior of said casing and said chamber to permit gas pressure built up within said casing to exercise 85 its force upon said piston to control the 90 raising and lowering of said flow line, and means carried by said flow line for closing said entry and arresting gas flow into said chamber when the operative pressure of the gas within the chamber reaches a predetermined point.
5. In oil well pumping apparatus, a casing, a flow line vertically shiftable within said casing, a flow valve in said flow line opened and closed by the vertical shifting 100 of said flow line, a cylinder, a piston in said cylinder connected with said flow line, an entry establishing communication between said casing and the interior of said cylinder permitting of the flow of gas from 105 said casing into said cylinder and into engagement with the piston provided there- 110 in to control the operating positions of said piston and said flow line, a closure provided upon said flow line and arranged to close said entry when the flow line has been elevated to a predetermined extent, and means for balancing the fluid pressure on 115 said piston to permit of the lowering of said flow line irrespective of the fluid pressures within said cylinder.
6. In oil well pumping apparatus, a casing, a flow line vertically shiftable within the casing, a stationary head at the upper end of said casing having a chamber formed 120 therein, an upstanding entry extending into said chamber and terminating in spaced relation from the bottom of said chamber, a piston within said chamber connected with said flow line, said entry permitting of the flow of gas from said casing into said chamber for engagement with the under side of 125 said piston, and a valved by-pass connec-

tion between the ends of said chamber on opposite sides of said piston to balance fluid pressures exercised upon said piston.

7. In oil well pumping apparatus, a casing, the flow line vertically shiftable within said casing, a stationary head surrounding said flow line above said casing, said head being provided with a piston chamber, a piston mounted within said chamber and connected with said flow line, a liquid seal between said piston and the walls of said
- 10 chamber, means for admitting gas from said casing into said chamber between the space provided between the under side of said piston and the surface of the liquid within said chamber, and a valved by-pass connection leading from said space to the top of said chamber and capable of balancing applied gas pressures upon said piston.

In testimony whereof I affix my signature.

JAMES W. TAYLOR.
